CONTROLLING MEANS FOR BATCH MACHINES

Russell Lee Brown, Lowell, Mass., Lewis J. Walters, San Diego, Calif., Spencer A. Coleman, Pelham, N. H., and Edward M. Brickett, North Chelmsford, Mass., assignors, by mesne assignments, to California Process Company, Los Angeles, Calif., a corporation of Nevada

Application January 17, 1936, Serial No. 59,634

3 Claims. (Cl. 19—92)

This application is a continuation-in-part of our application for Letters Patent on Wool cleaning machine, filed February 26, 1934, Serial No. 713,062.

5 The present application has particular reference to the timing means for controlling operation of machines of the type shown in our aforesaid application, and other so-called batch machines which intermittently operate upon 10 batches of material which are successively fed into the machine, then operated upon thereby, and then discharged therefrom; whereupon a fresh batch of material is fed to the machine, operated upon, and discharged.

15 The principal object of the invention is to provide novel means for variably controlling the time of the actual operation on the batch of material after it is fed into the machine and before it is discharged therefrom, and to do this 20 without necessarily varying the time required for the feeding in, or for the discharge of the batch, and if desired without varying the speed of rotation of the beater or other mechanism that operates upon the material in the machine.

25 Subsidiary objects are to provide separate controls for the feed mechanism, and for the discharge mechanism, so that the length of time that the material is retained in the operating chamber may be varied without changing the 30 times required for the operations of feeding material into such chamber, and for discharging it therefrom.

35 A further object of our invention is to provide separate controls for the feed mechanism and discharge door, so that the length of time that the stock is operated upon by the beater may be varied without changing the times required for the operations of feeding the stock into the duster and of discharging it therefrom.

40 A further object of the invention is to provide in combination with a machine having a chamber with an inlet and an outlet, means for operating upon material in said chamber; means for feeding material in the chamber, means for opening and closing the outlet of the chamber, means for varying the time of effective operation 45 upon the machine in the chamber, means for stopping the feed when the outlet is opened, and means for starting the feed when the outlet is closed.

45 The invention further provides in combination with a machine having a chamber with an inlet and an outlet, a rotary beater in said chamber, and means for rotating the beater; means for feeding material into the inlet of the chamber,

means for opening and closing the outlet of the chamber, means whereby without stopping rotation of the beater the outlet may be opened and closed at various time intervals, and means whereby the feed is operated after the outlet is closed, and stopped when the proper quantity of material is fed into the chamber.

5 Other minor objects of the invention will be hereinafter set forth.

To facilitate an understanding of the invention we will describe it as used in connection with a so-called "duster" of the type shown in our aforesaid application, and illustrated in the accompanying drawings; the claims concisely set forth, the novel combinations and arrangements 15 of parts and novel features of construction for which protection is desired.

In said drawings:—

Fig. 1 is a vertical sectional view of a "batch" machine equipped with our novel controlling 20 means.

Fig. 2 is a diagrammatic view of a timing means for variably controlling the operation of batch machines.

Fig. 3 is a diagrammatic view of a slight modification of the timing means for variably controlling the operation of batch machines.

Fig. 4 is an enlarged detail of the discharge door operating mechanism.

The batch machine shown in Fig. 1 comprises 30 a casing 1 in which is a rotatable beater 5 mounted upon a horizontal shaft 6, having pins 9 radially projecting from its periphery. Below beater 5 is an arcuate screen section 14 extending from the feed inlet 2a to an outlet opening 35 closable by a door 23. Below screen 14 is an air duct 15, through which screenings passing through screen 14 can be removed; or such screenings can be removed by mechanical means.

Above the beater is an arcuate screen section 40 17 extending from a point adjacent the outlet opening to a point adjacent the inlet. Adjacent the upper end of screen 17 is a throw-out pocket A having an adjustable wall or plate 25. Above screen 17 is an air duct 18 having an intake 20. 45 Through this duct light foreign matters which pass through the screen 17 can be removed.

The annular space between the periphery of the beater 5 and the screens 14, 17, etc. forms a chamber in which the material is operated upon 50 while in the machine.

A batch of material may be fed into said operating chamber through the inlet opening 2a in any suitable way. Preferably we use a feed conveyor 27 running over a driven roll 27a.

The construction and operation of the aforesaid machine is fully described in our aforesaid application and therefore further explanation thereof herein is unnecessary. Further the said 5 machine is merely referred to as illustrative and not limiting, as our invention is applicable to various kinds and constructions of "batch" machines.

The beater 5 may be rotated by any suitable 10 means. As shown it may be driven by a belt 29 from an electric motor 30, said belt running over a pulley on shaft 6, and a pulley on the motor.

The feed conveyor belt 27 may be intermittently driven by any suitable means. As shown (see 15 Fig. 2) it is driven by a belt 51, running over a pulley on roll 27a and a pulley on a stub shaft 56, carrying a gear 50, driven by intermediate gears 49-48 from a gear segment 47 on the floating member 42b of a magnetic clutch 42, loosely 20 mounted on a shaft 43, carrying the fixed member 42a of the clutch. Shaft 43 can be rotated by belt 44 running over a pulley 43a on shaft 43 and a pulley 45a of motor 45. The magnetic member 42a of the clutch 42 is fixed on shaft 43 25 and rotates therewith.

The floating member 42b of the clutch carries a cam 46 engaged by a pin 23d on an arm 23c attached to the hinge shaft 23a (Fig. 1) of discharge gate 23, and by oscillating arm 23c the 30 discharge gate can be opened and closed.

When the clutch is energized and during the time pin 23d is engaged with the annular portion 46d of the cam, the arm 23c will be depressed and hold the gate 23 in "closed" position as shown 35 in full lines in Fig. 1.

At the proper time during its rotation the cam will permit roller 23d to traverse portion 46a of the cam (which portion is curved on an arc coaxial with shaft 23a), and arm 23c will rise 40 and permit door 23 to drop into "open" position as shown in dotted lines in Fig. 1. Upon further rotation of cam 46 the arm 23c will be depressed by the portion 46c of cam 46 and close door 23 and hold it closed while pin 23d traverses the 45 annular portion 46d of the race.

The feed belt 27 and door 23 may be operated alternately and intermittently at the proper times by the motor 45, independently of the means which rotate the beater.

50 The magnetic clutch 42 is controlled by an independent timing circuit hereinafter described so that while the beater is rotated constantly, the length of time between the feeding and discharging operations may be varied to suit the particular material being treated; and thus the material may be subjected to treatment in the operating chamber for longer or shorter periods, without necessarily varying the speed of rotation of the beater.

60 *The time of beating*

The time required for proper treatment of batches of material in the machine will vary according to the kind and quality of the material, 65 and to enable this time to be readily varied we provide means for controlling the feed and discharge operations independently of the means for actually operating on the batch in the machine, so that the time required for feeding in 70 a batch of a given material and for discharging same after it is operated upon can remain constant; while the time interval between the feeding and the discharging operations may vary according to the lengths of the actual operations 75 on the material.

Fig. 2 diagrammatically illustrates the timing circuit. As shown, the magnetic clutch member 42a is connected in a circuit 38 including a source of electrical energy 39, and a normally closed switch 40-41 having one contact 40 projecting into the path of a stud 42c on the floating member 42b of the clutch, whereby once at each rotation of member 42b the switch 40-41 will be caused to open the electrical circuit 38.

The closing of circuit 38 is adjustably regulable 10 by a normally open switch 31-32, having its member 31 mounted on a spring 33 and connected to a solenoid 52. The switch 31-32 is closed at the desired intervals by a pin 34a on a gear 34 driven by intermediate gears from a 15 motor 37, which may be either an electrical or a time motor. When switch 31-32 is closed a circuit will be closed through the conductors 38, solenoid 52, and switch 40-41 and energize the magnetic clutch 42. The solenoid 52 will hold switch 31-32 in closed position until the said circuit is opened as described below.

When circuit 38 is closed the magnetic clutch is energized and the clutch member 42b, after making substantially one revolution opens the 25 normally closed switch 40-41. This opening is only momentary but the instant it is effected the circuit 38 containing the magnetic clutch, the switch 31-32 and the solenoid 52 is broken. As solenoid 52 is de-energized the spring 33 opens 30 the switch 31-32 and the circuit remains open until established again at switch 31-32. As gear 34 is continually revolved, stud 34a will at the desired interval of time again close switch 31-32. 35

When the magnetic clutch is energized cam 46 will be caused to turn one revolution, during which the discharge door 23 is first opened, and then closed; and the conveyor 27 is operated to feed in a fresh batch of material. When segmental gear 47 has made one revolution, pin 42c on clutch member 42b opens the normally closed switch 40-41; thereby de-energizing the clutch and stopping rotation of cam 46, and also de-energizing the solenoid 52 thus permitting switch 45 31-32 to open. The fly wheel effect of cam 46 is such that, after the contact at 40-41 is momentarily opened, the cam coasts far enough so that the contact is again established at 40-41. Then switch 40-41 again closes. But as gear 34 is continually revolved, stud 34a will at the desired interval of time again close switch 31-32. 50

By controlling the speed of rotation of gear 34 a variable total period for the complete cycle of operation is obtained; a portion of such cycle is 55 a fixed time for discharging, a fixed time for charging (such times being fixed in extent by reason of the constant speed of shaft 43 and the single revolution of gear 34) and a variable time of actual operation upon the batch of material in 60 the machine.

By providing separate controls for the feed and discharging periods, the length of time the material is operated upon in the machine may be varied, increased or decreased as desired without changing the times required for the feeding and discharging operations.

The timing unit (34-35-36-37) may be located at a point remote from the duster; as the shaft 43, operating the feed and discharge mechanism, is connected with the timing unit through the electrical circuit 38.

The time required for operation of the feeding and discharge can remain constant; but the time for the actual operation on material can be varied 75

according to the quality of the material being treated; for instance by means of our novel controls the feed may be operated for .03 of a minute and the discharge for .02 of a minute; while the beating operation may require from .05 to .50 of a minute, so that the total cycle of operations (including discharging, feeding and operation on or processing of material) would range from .10 to .55 of a minute respectively; in each of such 10 cycles the time of the actual operation is varied but the feed and discharge times remain unchanged.

Thus the time of the actual operation on material can be readily varied without affecting the actual times required for the operations of the feed or discharge, although the intervals between the feeding and discharging operations would vary according to the lengths of the actual operations on the material.

In the modification shown in Fig. 3, the mechanism operating on the material is driven by a belt 29 from an electric motor 30. The feed conveyor 27 may be intermittently driven by a belt 51 from a pulley on shaft 56, which carries a gear 50 driven by intermediate gears 48 from a gear segment 47 on the floating member 42b of a magnetic clutch mounted on a shaft 43 carrying the fixed clutch member 42a. The shaft 43 may be constantly driven by belt 44 from a motor 45. The floating clutch member 42b carries a cam 46c, engaged by a roller 113a on a bar 113 engaging an arm 23e attached to shaft 23a on which discharge door 23 is mounted.

When the clutch members are engaged cam 46c is rotated in the direction of the arrow, and while the roller on bar 113 is traversing the angular portion *x* of the cam, arm 23e will be kept in depressed position and hold the discharge door closed. As the cam rotates the roller 113a on bar 113 engages the part *y* of the cam which permits bar 113 to rise, and the door to move to "open" position, and remain open until the roller on bar 113 again engages portion *x* of the cam.

Clutch member 42a is connected in an electrical circuit 38, including a source of electrical energy 39, a solenoid 52, and a normally open switch 31-32, and a normally closed switch 40-41, the contact member 40 of said switch being engageable by a pin 42c on clutch member 42b, once during each rotation of said member, to open the switch and break the electrical circuit 38 to member 42a.

The interval of time between the closing of circuit 38 is regulated by the normally open switch 31-32, the member 31 of which is normally held open by a spring 31a. Switch member 31 is caused to contact with member 32 and close the circuit 38 at the desired time interval, by a pin 34a on a gear 34 driven by a reducing train of gears 35 from the motor 37. The closing of the switch 31-32 closes the circuit 38 through solenoid 52 and the normally closed switch 40-41 to the magnetic clutch member 42a; and solenoid 52 will hold switch 31-32 closed until the circuit is again opened by pin 42c opening the switch 40-41.

When circuit 38 is closed the magnetic clutch member 42a is energized, and cam 46c (which is fixed to clutch member 42b) is turned one revolution; during which the discharge door 23 is first opened and then closed; then the feed conveyor 27 is operated to feed a batch of material into the machine. When the cam has made one revolution pin 42c on clutch member 42b engages switch member 40, and opens circuit 38, thereby stopping rotation of cam 46c, deenergizing solenoid 52, and permitting switch member 31 to open, and the feed conveyor is stopped. As gear 34 is revolved, at constant speed, stud 34a will again close switch 31-32 at the desired interval of time. By controlling the speed of rotation of gear 34 a variable time period for operation on the material is obtained, while the times required for discharging material and for feeding in a fresh batch of material remain constant.

We claim:—

1. In a machine having a chamber provided with an inlet and a discharge; a processing member in said chamber; means for continuously actuating the member; means for feeding material into the inlet; a driving member; means independent of the member actuating means for continuously rotating said driving member; a driven member adjacent the driving member; remote control means independent of the driving member rotating means for intermittently causing the driven member to rotate through one revolution; and means operated by the driven member for opening and closing the discharge during the first part of each revolution of the driven member and for starting and stopping the feed during the remaining part of each said revolution.

2. In a machine as set forth in claim 1, said driving member and said driven member comprising a magnetic clutch in circuit with a normally closed switch adjacent the driven member adapted to be opened once for each revolution of the driven member; and said remote control means comprising a second normally open switch; and an electric circuit including said switches, a source of electric energy, and magnetic means for maintaining the second switch closed until the first switch is opened.

3. In a machine as set forth in claim 1, said driving member and said driven member comprising a magnetic clutch in circuit with a normally closed switch adjacent the driven member adapted to be opened once for each revolution of the driven member; and said remote control means comprising a rotatable disk; a second normally open switch adapted to be closed once on each rotation of the disk; an electric circuit including said switches, a source of electric energy, and magnetic means for maintaining the second switch closed until the first switch is opened; and means for rotating the disk at different speeds.
